DEAN C. SEITZ, OF CLEVELAND, OHIO, ASSIGNOR TO THE RUSS MANUFACTURING COMPANY, OF CLEVELAND, OHIO, A CORPORATION OF OHIO

SYRUP PUMP

Application filed February 5, 1929. Serial No. 337,694.

This invention relates to pumps for dispensing liquids from jars, and particularly to pumps used in connection with soda fountains.

5 The principal object of the present invention is to provide a syrup pump of novel and simplified construction, which is neat in appearance and economical to manufacture.

Another object is to provide a pump for 10 dispensing syrups and the like which may be easily operated without tiring the operator.

Another object is to provide a pump for dispensing syrups and the like with an operating lever having sufficient leverage to render the same easily operable while thick slow-flowing syrups, such as chocolate, are being dispensed.

A further object is to provide a pump for 20 dispensing syrups and the like with an operating lever having rolling engagement with the pump plunger rod, wherein friction is reduced to a minimum so that the same may be easily operated without tiring the operator.

A still further object is to provide a pump for dispensing syrups and the like with a lever handle having rolling contact with the plunger rod thereof, the tangent at the point 30 of contact of the handle with the plunger rod being substantially perpendicular to the axis of the plunger rod to minimize friction, so that thick syrups may be dispensed with a minimum effort on the part of the operator.

These being among the objects of the present invention, the same consists of certain features of construction and combinations of parts to be hereinafter described with reference to the accompanying drawings and then 40 claimed, having the above and other objects in view.

Heretofore pumps of the class used for dispensing syrups and the like, have been proposed which were operated by direct pressure on a spring pressed plunger. Thick syrups, such as chocolate and the like, are usually maintained at a comparatively low temperature, and as a result they will flow only when subjected to considerable pressure. It has been found from observations

that the soda fountain operator during rush periods often became very tired, because of the difficult operation of the directly operated pumps when dispensing heavy syrups, such as chocolate and the like. Quite frequently the operator's hands would blister, and his wrists would swell from continuous operation of the syrup pumps, thereby causing considerable pain.

55 Other pumps have been proposed which were operated by lever handles disposed at one side of the discharge spouts. These pumps, however, were awkward to operate because of their closeness to the spouts of adjacent pumps, and were unsightly because they were not symmetrical in design and did not blend in with the design of other parts of the soda fountain.

60 The present invention proposes a syrup pump which is extremely neat and pleasing 70 in appearance, and which is easily operable, even under the most severe conditions, such as dispensing the thickest slow-flowing syrups.

65 In the drawings which illustrate one suitable embodiment of the present invention,

Figure 1 is a longitudinal section taken 75 through a syrup pump showing the general construction of the same.

Fig. 2 is a plan view of the pump shown 80 in Fig. 1, showing the symmetrical arrangement of the exposed parts thereof.

Fig. 3 is an enlarged section of the upper portion of the pump showing the operating handle and its connection with the pump 85 plunger rod.

Fig. 4 is a transverse section taken on the line 4-4 of Fig. 3.

Fig. 5 is a fragmentary perspective view of 90 the operating lever showing the cam surface formed integral therewith.

Fig. 6 is a diagrammatic view showing the contact between the lever cam surface and the roller positioned on the pump plunger rod.

95 Referring to the accompanying drawings in which like numerals refer to like parts throughout the several views, the pump chosen for illustration is adapted to be positioned in a jar 10 which contains the syrup 100

or liquid to be dispensed, and is provided with a flanged cover plate 11 adapted to fit over the top of the jar 10 upon which the pump equipment is mounted. The pump cylinder and valve mechanism is supported 5 from the cover plate 11 by tubular members 12 and 13. One end of the supporting member 12 is suitably connected to the cover plate 11 and the other end of the same is secured in a lug 14 formed at one side of the pump 10 housing 15. The tubular member 13 constitutes a delivery tube for conveying syrup from the pump to the discharge spout 16 which is secured to the top of the cover plate 15 11. The upper end of the delivery tube 13 preferably telescopes with the discharge spout 16 and is securely held therein. The other end of the delivery tube 13 is received by and secured within a tubular passageway 20 17 formed in the pump housing 15. The tubular members 12 and 13 therefore provide a rigid support for connecting the pump mechanism with the cover plate 11.

The housing 15 is provided with a disc 25 valve 18 mounted in an opening in its base to control the flow of syrup from the jar 10 into the pump cylinder 21 formed within the housing 15. The pump cylinder 21 is connected by means of the port 19 with the passageway 17 so that syrup may be forced thereinto from the cylinder 21 on the downward stroke of the pump mechanism.

A plunger 20 having a free working fit within the pumping cylinder 21 is carried at 30 the lower end of a plunger rod 22. The upper end of the rod 22 is secured to the lower end of an upper plunger rod 23 extending through a spring housing 24, which plunger rod 23 has a recessed member 25 threaded onto 35 its upper end that has sliding contact with the walls of the housing 24. The upper plunger rod 23 is preferably square in cross section and is held against rotation by the square opening 40 formed in a bracket 27 attached to the cover plate 11. The lower end 40 of the rod 23 is formed to a cylindrical shape and formed with threads so that it can be threaded into an internally threaded collar 41 secured to the upper end of the lower rod 22. The spring housing 24 is supported 45 within the bracket 27. A compression spring 26 surrounds the rod 23 and its ends abut against an annular plug 39 threaded into the bottom of the housing 24, and against the 50 bottom of the recess formed in the member 25 so that the compression pressure of the same will normally hold the plunger 20 at its uppermost position in the pump cylinder 55 21.

The pump just described has been chosen for illustration and explanation as one form of pump to which the present invention, which is about to be described, is adaptable, 60 and it is to be understood that this invention

is also adaptable for use with many other types of syrup pumps.

The bracket 27 attached to the cover plate 11 is formed with an integral arm 28 extending outwardly and upwardly therefrom. A 70 push rod 29 is slidably positioned in the bracket 27 parallel to the axis of the lower and upper plunger rods 22 and 23, and in the same vertical plane as the spout 16, the member 25 and arm 28, as illustrated in Fig. 2. 75 As shown in Fig. 3, the lower end of the push rod 29 is positioned below the cover plate 11 and is secured by a nut 44 to an arm 30 which is mounted on the cylindrical end of the upper plunger rod 23 between the shoulder of the plunger rod 23 and the collar 41, and normally abuts against the bracket 27 to prevent withdrawal of the plunger 20 from the pump cylinder 21. The upper end of the push rod 29 is bifurcated and carries a pin 80 32 between its legs 33 upon which a roller 31 is mounted. The top surface of the roller 31 is preferably positioned below the tops of the legs 33 substantially as shown in Fig. 4.

A channeled lever 34 is pivoted by means 85 of a pin 35 to the end of the bracket arm 28 and is formed with a cam 36 intermediate its side flanges. The metal of the lever 34 connecting the side flanges thereof preferably extends beyond the pivot pin 35 so that an 90 abutment 42 is provided which engages the bracket arm 28 when the lever is in its normal uppermost position to prevent the lever from being pivoted to an inoperative position. The cam 36 is adapted to engage the 95 roller 31 and is positioned between the legs 33 of the upper end of the push rod 29 so that it is guided thereby. The face of the cam 36 is preferably designed in such a manner as shown in Fig. 6, so that regardless of the 100 pivoted position of the lever 34, the point of contact with the roller 31 is slightly in advance of the longitudinal axis of the push rod 29 so that friction produced by rotation of the cam roller 31 will be reduced to a minimum as the lever 34 is pivoted to move the 105 push rod 29 downwardly. It is preferable that this point of contact be no more than four degrees in advance of a point on the 110 roller surface which lies on the longitudinal axis of the push rod 29 in order that a thrust 115 pressure will not be exerted on the rod 29 which would tend to bind the same in the bracket 27. In some instances, however, it 120 may be desirable that the point of contact of the cam 36 with the roller 31 be coincident with the axis of the push rod 29. It might be said that the cam surface is designed so that a tangent "T" to the cam surface at the 125 point of contact with the roller 31 will be constant for all pivoted positions of the lever 34, as shown by the two positions "A" and "B", and that the angle of the tangent to the 130 longitudinal axis c of the push rod 29 may vary between the limits of zero and three or

four degrees, depending on the particular design and size of cam 36 and roller 29. It can be seen in Fig. 6 that the tangent "T" to the cam curve at the point of contact when the cam and roller are in position "A" is parallel to the tangent "T" when the cam and roller are in position "B". In other words, the point of contact of the cam and roller relative to the axis *c* of the push rod 29 remains constant for all positions.

It is to be understood that the word "substantial" when used in the claims in connection with the tangent to the cam at the point of contact of the cam and roller, is to include manufacturing tolerances. In other words, it is to be understood that when the tangent to the cam surface at the contact point is spoken of as being substantially perpendicular to the axis of the push rod, it may lie at any angle coming within reasonable manufacturing tolerances. By way of explanation, the openings in both the handle 34 and bracket 28 may be shifted a slight amount from their correct predetermined position by an inadvertent misplacement or shifting of the bracket or handle in the fixtures or jigs when the openings are drilled or formed. Manufacturing tolerances, in practice, are prescribed to compensate for these conditions.

As shown in Figs. 1, 2 and 3, the lever 34 is formed with an opening 37 near its free end, into which a plate 38 bearing the name of the syrup to be dispensed, may be positioned and held therein by a threaded cap 43.

In operation, the soda fountain operator pushes downwardly on the end of the lever 34 which by reason of the contact between its cam 36 and the roller 31, actuates the push rod 29, to move the plunger 20 to exert pressure against the syrup contained within the pump cylinder 21. The syrup is forced through the port 19 into the passageway 17, and thence through the discharge tube 13 into the spout 16 where it is discharged at the mouth of the same. When the plunger 20 reaches the bottom of its stroke the operator removes his hand from the lever 34, and the spring 26 which has been compressed during the down stroke causes the plunger to return to its normal position to create a suction to raise the valve 18 from its seat and draw syrup into the pump cylinder 21.

The push rod 29 being rigidly secured to the arm 30 which is securely held between the collar 41 and shoulder of the upper plunger rod 23 is held against rotation so that the correct position of the cam 36 will always be maintained between the sides 33 of the bifurcated end of the push rod 29.

The pump operating mechanism just described provides a construction wherein considerable leverage is provided and wherein friction is reduced to a minimum by the use of the cam 36 and roller 31. It can be seen

that many disadvantages present in syrup pumps used heretofore may be practically eliminated by incorporating the operating mechanism of the present invention. It is apparent that the thickest syrups, which are the most difficult to dispense, may be easily dispensed without tiring the soda fountain operator, because of the improved operating mechanism described.

It is further apparent that a construction is provided which is symmetrical in design and consequently neat in appearance because practically all operating parts are concealed by the lever 34 or the cover plate 11 when the pump is in position in the jar 10. The side flanges of the lever 34 conceal the roller 31, cam 36, and the upper end of the push rod 29, and the cover plate 11 conceals the connection between the lower end of the push rod 29 with the actuating rod 23.

Furthermore, it is to be understood that the apparatus shown and described, and the particular procedure set forth, are presented for purposes of explanation and illustration and that various modifications of said apparatus and procedure can be made without departing from the spirit and substance of the broad invention, the scope of which is commensurate with the appended claims.

What I claim is:

1. In a syrup dispensing pump, a plunger, a plunger rod connected thereto, a push rod offset from and rigidly connected to said rod, and a hinged operating lever having unconnected sliding engagement with said push rod for actuating said plunger.

2. In a syrup dispensing pump, a plunger, a plunger rod connected thereto, a push rod parallel to said rod and rigidly connected therewith for simultaneous longitudinal movement in the same direction, and a hinged operating lever having a cam surface thereon in unconnected engagement with said push rod, whereby movement of said lever causes said cam surface to depress said push rod for actuating said plunger.

3. In a syrup dispensing pump, a plunger, a plunger rod, a push rod connected to said rod in parallel offset relationship to simultaneously move therewith in the same direction for actuating said plunger, a hinged operating lever, and a curved cam on said lever having engagement with said push rod, the tangent to the cam curve at the point of contact between said cam and push rod being substantially perpendicular to the longitudinal axis of said push rod for all positions of said lever and push rod.

4. In a syrup dispensing pump, a plunger, a plunger rod, a push rod rigidly connected to said rod in parallel offset relationship to simultaneously move therewith for actuating said plunger, a roller mounted on said push rod perpendicular to the axis thereof, and a pivoted operating lever having a cam sur-

face thereon contacting with said roller, the tangent to said cam surface at the point of contact with said roller being substantially perpendicular to the axis of said push rod for all pivoted positions of said lever.

5. The combination with a syrup dispensing pump having a plunger rod connected with a plunger, of a push rod rigidly connected to said rod in offset relationship for 10 simultaneous longitudinal movement in the same direction, and a pivoted lever for actuating said push rod having an integral cam surface thereon in contact with an end of said push rod at a point substantially coincident with the longitudinal axis of said rod for all 15 pivoted positions of said lever, whereby movement of said lever causes said cam to depress said push rod to actuate said pump plunger.

6. The combination with a syrup dispensing pump having a plunger rod connected with a plunger, of a push rod connected with said rod in offset parallel relationship, said plunger rod and push rod being simultaneously movable in the same direction, a roller 25 rotatably mounted on the end of said push rod, the axis thereof intersecting the axis of said push rod, a pivoted lever for actuating said push rod, and a cam surface carried by said lever contacting with said roller, the 30 tangent to said cam surface at the point of contact with said roller being disposed substantially perpendicular to the axis of said push rod for all pivoted operating positions of said lever.

35. 7. The combination with a syrup dispensing pump having a longitudinally movable rod connected with a plunger, of a push rod parallel to and rigidly connected with said rod for simultaneous movement in the same 40 direction, said rod being provided with a bifurcated end, a roller positioned between the sides of said bifurcated end transversely of the axis of said push rod, a pivoted lever for actuating said push rod to operate said plunger, and a cam surface carried by said lever 45 contacting with said roller substantially on the axis of said push rod whereby pivotal movement of said lever causes said cam surface to move along said roller and depress 50 said push rod.

8. The combination with a syrup dispensing pump having a longitudinally movable rod connected with a plunger, of a push rod 55 parallel to and connected with said rod for moving the same, a roller positioned on the end of said push rod transversely of the axis thereof, a downwardly presenting channel-shaped pivoted lever for actuating said push rod, and a cam surface integral with and positioned between the side flanges of said lever in 60 contacting relationship with said roller, the tangent to said cam surface at the point of contact with said roller being disposed substantially 65 perpendicular to the axis of said

push rod for all pivoted positions of said lever.

9. A syrup dispensing pump comprising a cover plate, pumping mechanism supported by said cover plate, a longitudinally movable rod connected with said pumping mechanism and guided in said cover plate, a bracket secured to said plate, a longitudinally movable push rod extending through said bracket and connected with said rod below the surface of said plate, and a lever for actuating said push rod pivoted to said bracket, said lever being provided with a cam surface contacting with said push rod, whereby pivotal movement of said lever will cause said cam surface to longitudinally move said push rod for actuating said pumping mechanism.

10. A syrup pump comprising a cover plate, pumping mechanism supported by said cover plate, a bracket secured to the upper surface of said plate, a pump rod connected with said pumping mechanism and extending through said bracket, rod guiding means carried by said bracket, a push rod longitudinally movable in said bracket and connected with said pump shaft below said plate, a roller mounted in the end of said shaft extending above said plate, and a lever for actuating said push rod having engagement with said roller so that movement of said lever against said roller longitudinally moves said push rod to operate said pumping mechanism.

11. A syrup pump comprising a cover plate, pumping mechanism supported by said cover plate, a bracket secured to the upper surface of said plate, a plunger rod, rod guiding means carried by said bracket, an auxiliary push rod slidably carried by said bracket connected to said plunger rod, a lever pivoted to said bracket and having cam engagement 140 with the end of said push rod, and a discharge spout connected with said pumping mechanism, the longitudinal axis of said spout, operating lever, rod guiding means and supporting bracket being disposed in the same 145 vertical plane.

12. In a syrup dispensing pump, a plunger, a reciprocal plunger rod connected to said plunger, a thrust-transmitting portion carried by said plunger rod, and a hinged operating lever having disconnected sliding engagement with said thrust-transmitting portion at a point offset from the axis of said rod for actuating said plunger.

In testimony whereof I affix my signature.

DEAN C. SEITZ.
